UNITED STATES PATENT OFFICE

WILLIAM HATTON, OF ANTWERP, BELGIUM, ASSIGNOR TO INTERNATIONAL STANDARD ELECTRIC CORPORATION, OF NEW YORK, N. Y., A CORPORATION OF DELAWARE

AUTOMATIC TELEPHONE SYSTEM

Application filed September 20, 1930, Serial No. 483,233, and in Great Britain October 16, 1929.

This invention relates to automatic or semi-automatic telephone systems, and is more particularly concerned with telephone networks comprising main and satellite exchanges, in which for calls originating in a satellite, a junction to the main exchange is automatically taken into use.

There are two known types of satellite arrangements. In one of these the subscribers at the satellite are provided with impulse sending devices and both local and outgoing calls are made automatically, discrimination taking place either at the satellite or at the main exchange. In the second type the junction to the main exchange terminates at an operator's position and all the calls both local and outgoing are completed by the operator. In both cases the junction is released for a local call.

The present invention relates to a modification of the first arrangement. It has been proposed in certain full automatic networks of this type to provide zone metering throughout the system. It has been found inconvenient, however, to install such a system completely in certain instances and in such instances it has been found convenient that calls between various exchanges of the network or between certain of these exchanges should be semiautomatically completed by the aid of an operator at the main exchange. In such a case metering records would be taken by the operator.

According to one feature of the invention local calls within the satellite are completed automatically while calls outgoing therefrom are routed over a junction to an operator's position at the main exchange. A satellite subscriber will, therefore be provided with an impulse sending device and discrimination must take place in accordance with the number dialled as to whether the call is local or outgoing. Since the operator is not required if the call is local, it will be inconvenient to signal the operator immediately the junction is taken into use, that is before dialling has commenced and therefore before discrimination has taken place.

In accordance with another feature of the invention therefore, in a telephone network

comprising a main and a satellite exchange, on the initiation of a call at the satellite exchange, a junction to the main exchange is automatically taken into use, terminating at an operator's position but the operator is not called unless the call is outgoing from the satellite.

According to a further feature of the invention if the call is local to the satellite the junction is released unused.

Other features of the invention will be apparent from the following description of one embodiment of the invention and will be set out in the statement of claim.

A general description will now be given of a layout shown in Fig. 1 of the accompanying drawings of the embodiment of the invention to be described in detail later. The network to be described has a 4 digit numbering scheme.

In this embodiment a main or centre exchange C is shown having connected thereto a single satellite exchange TS. This satellite is of the tandem type and has connected thereto another exchange S. It will, of course, be obvious that more than one satellite may be connected to the main exchange and that more than one exchange S may be connected to the tandem satellite TS. It will be obvious that all calls originating in the tandem group, that is in any one of the exchanges TS and S, proceed exactly as if they originated in TS. A toll position TP is provided at the main exchange and all calls between C and TS in both directions will pass therethrough. Toll calls from any part of the network will also be handled at this position. When a subscribed RS in TS or S calls he will be automatically connected via a link circuit L, an outgoing junction circuit OJC, and a both-way junction circuit BWJC to a jack RL at the toll position. A register circuit MCC will be connected up to OJC. It will be seen that the junction is both-way and has two branches at the main exchange, one incoming to the toll position and the other outgoing from the automatic equipment. When a call is initiated as described above, both these branches are busied. The subscriber receives dial tone from the operator's posi-

tion but no signal is at present made thereto. The subscriber dials into register MCC. In the example shown in which the total capacity of the satellite group is 100 lines discrimination takes place after two digits and if the call is found to be local, the junction and the register are released and the last two digits operate the final finder switch of the satellite. If, however, the call is outgoing, release will not take place after two digits and two further digits will be received by the register. The magnitude of the digits is not recorded but switching operations take place on the reception of each digit. These switching operations indicate that the call is outgoing and the signal is then sent over the junction to the operator's position to light a lamp CL. The operator will enquire the wanted number and will complete the call automatically over the multiple M. When a call is originated in the main exchange C the subscriber is connected over the first and second line finders, 1LF, 2LF, to a link circuit to which a register-sender RG becomes attached. The subscriber dials into the register and the register then sends out trains of impulses in the usual way. If the call is local to the main exchange, the call is set up over automatic switches as usual. If, however, the call is outgoing either for a call within the network or a toll call the call would be routed over one or two group finders, such as at 1GF, 2GFS to a network recording jack NR or a toll recording jack TR at the toll position. These pieces are reached by a less number of digits than normally and it is necessary to provide some means whereby the register will be released and the connection switched through. These operations normally take place when the full number of digits have been sent out from the register. Instead of providing digit absorbing arrangements or the like, a signal is sent back immediately the toll position is reached, whereby switching operations take place to release the register and switch through the connection. Without further loss of time. The operator will complete calls within the network over the multiple M as before. As has been stated the selecting stages are of the finder type with control circuits CC. The operator at TP is provided with cords TC comprising dials D. Toll lines TL are also incoming to the position.

It is considered sufficient to illustrate the invention by describing

(1) The initiation of a call from a satellite subscriber RS in TS, the method of discrimination between local and outgoing calls, and the means for signalling the operator.

(2) The setting up of a call from a main exchange subscriber CS to a jack NR at TP.

These calls will be described with reference to Figs. 2-A to 5-B of the accompanying drawings. Figs. 2-A and 2-B show a

subscriber's line and starting circuit at the satellite exchange together with a link circuit comprising a line finder SMF and one or two final finders SMS, together with a control switch SM. Each final finder is a single motion switch having access to a maximum of 50 lines. When a link circuit is taken into use one of the finders hunts automatically for an idle outgoing junction connected in its banks. If a call is found to be for a local call the junction is released and one or other of the final finders is set to the wanted line in accordance with the last two digits dialled.

Fig. 3-A and 3-B comprises an outgoing junction circuit OJC with its associated register MCC and also the both-way junction circuit BWJC and the jack RL and TP.

Fig. 4-A shows the second line finder circuit at the main exchange.

Figs. 5-A and 5-B show the register sender at the main exchange associated with the second line finder.

Figs. 4-A and 4-B show the first group finder of the single motion type with its control circuit, indicates the second group finder similar in arrangement to the first group finder, and shows also the recording trunk circuit and the jack NR at the toll position.

Figs. 2-A and 2-B with Figs. 3-A and 3-B show the circuits for the first arrangement and should be arranged with Figs. 3-A and 3-B to the right of Fig. 2-B and Fig. 3-B below Fig. 3-A.

Figs. 4-A, 5-A, 5-B, 4-B and 4-C show the second circuit arrangement and should be arranged with Figs. 4-B and 4-C to the right of Fig. 4-A, Fig. 5-A below Fig. 4-A and Fig. 5-B below Fig. 5-A.

Referring now to Figs. 2-A, 2-B, 3-A and 3-B. When a subscriber at the satellite exchange lifts his receiver relay L_r operates, and at its front contacts operates the common starting circuit relays L_{sr}, S_{tr}, and circuits are closed for the stepping magnets of the idle call finders in the local link circuits: battery, SMF and its interrupter contacts, front contact of S_{tr}, B_J, L_{t1}, normal contact of magnets SMS, A₄, wiper S_{m1}, E₃, M_{c3} earth.

When the call finder finds the calling line relay L_t operates, earth, upper winding of L_t, B_J, wiper e of SMF to battery on front contact of L_r. SMF is stopped and relay A now operates; battery, via thermostat contact TH, A, L_{t1}, normal contact of SMS to earth as above for magnet SMF.

SMS now hunts for a free outgoing junction; battery SMS and interrupter contact A₂, T_{c4}, J_{t1}, earth.

Test relay J_t operates on an idle junction to stop hunting, earth A₁, wiper S_{mse}, J_t, wiper S_{m4} and normal contact, wiper S_{mse}, D_{r2}, T_{hr}, via back contacts of the line and cut-off relays of the incoming junction circuit L_{cr3} to battery; relay D_{1r} of the junc-

tion circuit operates in parallel. Relay Mc operates in turn via wiper sm_5 , Lm_1 , Pb_4 , Jt_1 to earth. Earth on Mc_3 shorts a non-inductive winding of Jt to busy the junction, 5 and also operates Lb . The subscriber's cut-off relay now energizes in series with relay E to earth at Lb_1 , so that Lr is released, and the subscriber connected through to the junction. Lt is held by earth on A_3 and in turn 10 holds A .

When the outgoing junction is seized, relay Isr operates over the calling loop, followed by Lbr and Ar in obvious circuits. Relay Dr now operates via Ar_4 and locks to D_1r_1 . 15 The battery potential operating Jt is maintained at Ar_1 when Dr_2 opens. Ground at Isr_2 is connected via Ar_5 , Br_1 , Cr_3 , the junction B wire, $J1rt_2$, AJ , $Asrt$ to battery. Relays $Asrt$, Brt , Art operate in turn. The operation of relay Ar in the OJC also connects battery over Er_1 , Ar_2 so that the common start relays $Strm$, Crm of the register circuit RC operate. The finder switch SMF now 20 hunts for the calling junction; SMF and its interrupter contacts, front contacts of Crm , $Jtrm_1$, earth. When the junction is reached $Jtrm$ operates from the battery traced above over wiper a , left hand winding of $Jtrm$, normal contact of SMT , normal contact and wiper 25 as , Arm_1 to earth. Arm then operates from earth at $Jtrm_1$, and connects earth to the low resistance right hand winding of $Jtrm$ to busy the junction. A circuit is formed from battery, Er in OJC, C_1r , wiper c , Arm_4 , 30 normal contact and wiper bs , $Lmrm_1$, Arm_5 , earth. Relay C_1r only operates and closes a circuit; battery, Cr , C_1r_1 , Isr_1 , earth.

Dial tone is now connected up from the manual incoming junction circuit; the tone 40 is connected from lead DT , $Bsrt_1$, Art_1 , to a coil from which it is induced in other coils connected to both junction wires. Dialled impulses are received by Isr which repeats them at its contact 1 over wiper b , Arm_3 , 45 $1mrm$, Cnr_1m_2 , Cnr_1m_1 , SM_1 to battery. Switch SM_1 steps on at each impulse and $Lmrm$ energizes throughout the digit and releases relays C_1r , Cr in O. J. C. so that dial tone is disconnected. Slow release relay Brt 50 in the manual circuit prevents interference by dialling. Directly SM_1 steps, off-normal switch SMT begins to hunt for the group of terminals marked by wiper es ; battery SMT and its interrupter contacts es , $Ltrm_2$, Cnr_4 , 55 Arm_5 to earth. When SMT finds the marked contact, relay $Ltrm$ operates via Cnr_1m_1 , et , es , battery, and with $Lmrm$ released and $Ltrm$ operated, Cnr_4 energizes; battery Cnr_4 , Cnr_4 , $Ltrm_1$, bs , $Lmrm_1$, Arm_5 , earth and 60 locks up. The next digit is therefore repeated direct to SM_1 via Cnr_4 . $Ltrm$ releases and at the expiration of the digit, relay Cnr_1m operates; battery Cnr_1m , Cnr_1m_4 , Cnr_3 , $Ltrm_1$ to Arm_5 as above; and locks up. On 65 the next digit being dialled, $Lmrm$ again op-

erates to battery via cnr_1m_2 so that relay Dcr_1m operates; Dcr_1m , Dcr_1m_2 , Dcr_2m_4 , Cnr_1m_3 , $Lmrm_1$, Arm_5 , earth. Dcr_1m locks via Dcr_1m_2 , Dcr_2m_2 , Ar_5 , at the end of the digit. At the next digit, Dcr_2m operates and locks up similarly releasing Dcr_1m . If the first digit was even, relay Etr operates, via ds , Cnr_4 , Arm_5 . 70

Local call

If, however, the call is a local one, earth is connected after SMT is set from Ar_5 , Cnr_1m_4 , Etr_1 , at (or bt), jumpering point, $Merm$, Lcr , to battery. $Merm$ operates and connects relay Lcr in parallel to itself at $Merm_1$. Test battery is disconnected at Lcr_3 so that relay Jt (Fig. 2-B) in the link circuit releases, followed by Mc (Fig. 2-A). Relay As (Fig. 2-A) of the local transmission bridge operates. The junction is disconnected so that the outgoing junction circuit, the register circuit and the manual junction circuit releases. The last two digits then operate in the link circuit to complete the local connection. 85

Outgoing call

For an outgoing call, the normal 4-digit number of the wanted subscriber is dialled. Since the very fact that more than two digits are received in MCC is conclusive that the call is outgoing, no jumpering via SMT is necessary, but after the fourth digit has been dialled and Dcr_2m is operated, a circuit is formed from battery Er in OJC, C_1r , c , Arm_4 , Dcr_2m_1 , Dcr_1m_1 , $Lmrm_1$, Arm_5 , to earth. Er 90 operates in this circuit, connecting battery via relay Cs_1r , Br_4 , Er_4 , Ar_3 , to the A wire of the junction thereby operating relay $Bsrt$ via AJ , and Art_2 . Lamp CL is now lighted to warn the operator of an incoming call. 95

Relay $Jtrm$ in MCC releases, so that MCC returns to normal.

On plugging in, all the incoming junction relays are released, but battery potential designating an idle junction which was previously cut off at Art_4 , is still disconnected at AJ . 100

For special service two digit numbers are allocated, the first digit being 0. After the second digit has been dialled, relay Er in OJC is operated from earth via Arm_5 , Cnr_1m_4 , wiper fs and its tenth contact, Arm_4 and wiper c . 110

If discrimination is to take place after the first digit, the points a should be connected so that earth is connected to wiper a or bt via $curm_2$, $ltrm_3$ jumpering point a , etr_1 , to operate $Merm$ after the first digit if the call is local. In this case, 0 only would be dialled 120 for special calls and Er would be operated from the earth referred to above via a and wiper fs . 125

An outgoing call from the main exchange will now be described with reference to Figs. 130

4—A, 5—A, 4—B and 4—C, which should be arranged with Fig. 4—B to the right of Fig. 4—A and Fig. 5—A below Fig. 4—A.

Ground from the line finder starting circuit operates the finder magnet PL in a circuit via BJ, Ar1, Fr3, Gr1, Dr4, PL to battery. On reaching the calling 1st line finder, relay Ar operates via wiper d, BJ, left hand winding of Ar, to the starting circuit. Cr operates from ground on the start wire, Ar1, left hand winding of Cr, Dr5 to battery. Ar is now held from earth on Cr1 via its low resistance winding which busies the 1st line finder. Relay Br now operates via Cr3, Ar1, to start lead, and in turn closes a circuit from earth via Br1, Gr4 for relay Dr so that relay Hr energizes in series with the calling subscriber's cut-off relay via Dr3 over wiper c. Supervisory relay Sr energizes over the subscriber's loop and contacts Dr1, Dr2.

Relay Cr locks up via Cr4, Er3, Dr5 to battery and Br remains energized via Hr2, Sr1. Battery via Dr5, Cr2, energizes relay Str which closes a circuit for Csr, and the free registers start hunting for the calling line finder circuit, in circuits such as battery PR, Ter2, Csr1, Rtr1, LJ, RK to earth. The test relay Rtr of the first register to reach the calling trunk energizes in a circuit; battery Dr5, Cr2, wiper g, high resistance left hand winding of Rtr, Lr3, normal contact and wiper c of switch SMA, R2r1 to earth, PR1 is released and relay Tcr1 energizes via Rtr1, LJ and RK to earth, busying the trunk circuit by connecting earth via low resistance winding of Rtr to wiper g. Relay Ter then operates in an obvious circuit and connects up dial tone coil DTC to transmit a tone to the calling line from its right hand winding via Tcr5, wiper a, Fr6, to the a wire, and via Tar5, Ter4, wiper b, Fr1 to the b wire. Relay Rbr operates; battery Rbr, interrupter contact of switch SMA, wiper a of switch SMA and contact Ter1 to earth, and energizes magnet SMA which releases Rbr and steps to its first contacts when Rbr again energizes to earth on second contact of wiper a of switch SMA and SMA steps to its second contact. The digit impulses are repeated at Sr1 via wiper c, Ter3, to relays Isr, S1r in series, and Isr repeats these in turn to register switch SMTH in a circuit; earth R2r1, Pgr6, Isr1, wiper d of switch SMA, magnet SMTH to battery. Relay S1r remains energized during the digit and energizes Rbr which locks up via interrupter contacts of SMA and Rbr1. A circuit is now formed from battery on Dr5 of the line finder circuit, lower winding of Er, wiper d, winding of C, Rbr4, wiper c of switch SMA, r2r1 to earth. Relays Er and C energize and the former disconnects dial tone and releases relay Cr. Test potential is removed and relay Rtr releases but relay Tcr1 holds in a circuit via

C1, LJ, RK to earth, and in turn maintains Ter operated.

At the end of the digit, S1r releases so that SMA operates via Rbr3, S1r1, releases Rbr and steps to its second contacts.

The remaining digits are similarly received on SMH, SMT and SMU, SMA stepping on between each digit.

When SMA is on its fourth contacts after two digits had been received relay Tar operates via wiper c of switch SMA to earth on R2r1.

Earth is now connected via relay B, Tar3, Ter5, wiper a, Fr6, to the a wire; and battery is connected from Tar4, home contact and wiper X of impulse sending switch PI, Tcr4, wiper c, Fr1, Cr5 to the b wire.

Relay Ara in the control circuit of the first group finder operates via J1r1 in the finder circuit, J2r2 and the b wire. Ecr energizes, so that switch SMB hunts in a circuit; battery, SMB, interrupter contact, Ecr1, Bcr1, Fer3, to earth. When the calling trunk is reached, test relay Bcr energizes in a circuit via Gc1r3, wiper cb to the b wire as above. Relays Fer in the control circuit and J1r in the finder circuit now operate in series; Fer, J1r, wiper bb, Bcr1, Fer3 to earth, and lock via J1r2, J2r1 and Br1 in the line finder circuit. Switch SMB now returns to normal in a circuit; SMB and its interrupter contact Gc1r5, Fer2, off-normal arc and wiper db, to earth. Relay Bcr releases and Gcr operates from earth on wiper db. A loop is now formed from the register via the a wire J1r4, relay Bra, Gcr2, J1r1, J2r2 to the b wire. Relay B in the register operates. Relay B energizes Lr in an obvious circuit. Lr short circuits B at Lr2, and locks via wiper Y of PI, Lr4. Relay Bra in the control circuit now operates. The impulse sending switch now begins to rotate; battery PI, Lr1, D2r2 to earth.

At each step of PI, Bra is impaled, and steps switch SMB in a circuit; battery, SMB, Ira, Gc1r1, Gcr1, Bra1, earth. After the required number of impulses have been sent out, relay Nir operates via D1r4, wiper b of switch SMTH and the contact on which it stands, the contact of wiper Z of PI connected thereto, wiper Z to earth. Relay Nir short-circuits the impaling wiper X at Nir1, and locks up via Pgr1, Nir2, Lr6 to earth. When the control switch SMB left its home contacts the energizing circuit for Gcr was opened, but this relay was held via Ira1, Fer3 until the end of the digit when it releases and opens the forward loop.

When PI reaches contact 13 relay D1r operates via wiper Z and locks via D1r3 and Tc1r3. When wiper Y leaves its off-normal arc, relays Lr and Nir release, and PI stops.

With Gc1r operated and Gcr released, a circuit is formed from earth on Gc1r6, over Gcr3, Hcr1, J1r3, PJ, to battery, and the

group finder hunts for an idle contact marked by the control switch. When an idle marked contact is reached, test relay Hcr operates; earth, $Fcr3$, left hand high resistance winding of Hcr , $Gcr4$, wiper ab , wiper dj , J_1r5 , 5 wiper cj , $Brr1$, to battery. Hcr locks in series with Scr which also operates. PJ is disconnected. Relay J_2r operates; battery Scr_1 , J_2r , J_1r2 , J_2r1 , $Br1$ in the line finder 10 circuit to earth. Relay J_1r is released at J_2r_1 to disconnect the control circuit and J_2r locks via J_2r_1 and $Br1$. J_2r connects the speaking conductors through to the second group finder. The second group finder control circuit operations are identical with 15 those of the first group finder control circuit, and the second digit is sent out as before under control of SMH , since the circuit for Nir is now via Pgr_1 , D_1r4 , D_2r_4 to wiper b in switch $SMTH$. At the end of the digit, the 20 second group finder finds a toll recording trunk and the register relay D_2r operates via contact 12 of wiper Z and D_1r2 . The group finder finds battery via $Brr1$ on the 25 c wiper. Relay Drr of the toll recording trunk operates from the battery and earth over the a and b wires from the register and energizes relay Arr which puts earth on the fourth wire. A calling lamp CL is 30 lighted.

Earth on the fourth wire is connected back through the group finder circuits to operate relay Gr in the second line finder circuit. Relay Gr releases Dr at $Gr4$ and Dr releases 35 Er , Cr , Tc_1r and Ter in the register. Rr now operates via off-normal bank of wiper b of switch SMA , C , LJ , RK to earth and energizes R_2r . $SMTH$ now homes; earth, 40 interrupter contacts of register magnets, R_2r_2 , off-normal arc and wiper a of switch $SMTH$, $SMTH$ to battery; the other registers in turn home, after which the circuit is transferred to relay Rbr via the normal contacts of all the register a wipers and wiper a 45 of switch SMA , so that SMA in turn homes.

Relay Gr also connects the a and b leads through in a metallic circuit at $Gr5$, $Gr3$.

Relay Drr in the recording circuit holds 50 over the junction until the operator plugs in when relay Brr operates to disconnect CL and Drr , and holds Arr . The calling subscriber is fed from the operator's cord.

What is claimed is:

1. In a telephone exchange system the combination of a main exchange and a satellite exchange, an operator's position, automatic switching mechanism at each exchange provided with banks, a junction line extending from the satellite exchange to the main exchange terminating in two branches, one leading to the operator's position and the other leading to the banks, and means whereby calls can be extended over each branch. 55

2. In a telephone exchange system the combination of a main exchange and a 60

satellite exchange, means for originating calls at each exchange, a register sender at the main exchange, an operator's position at the main exchange, means controlled by calls originated in the main exchange for connecting with said register sender, and means controlled when a call is routed to said operator's position to cause the release of said register sender. 70

3. A circuit arrangement for a telephone exchange system comprising a main exchange and a satellite exchange to which lines are connected, a junction line extending to the main exchange, means for initiating a call at the satellite exchange, an operator's position, a register sender, and means for passing calls from the main to the satellite exchange through the operator's position, said calls comprising potential placed on one of the wires of the trunk and a relay connected to said register sender whereby the register sender is disconnected from the circuit and the talking conductors of the trunk are switched through. 80

4. A circuit arrangement for a telephone exchange system comprising a main exchange, a plurality of satellite exchanges of the tandem type to which lines are connected and discriminating means adapted to discriminate for all calls originating in the 85 tandem group as if all the subscribers were located in the tandem satellite. 90

5. A telephone exchange system comprising a main exchange and a satellite exchange, an operator's position and a selector stage 100 wherein there are two-way junctions each junction terminating at the main exchange in two branches, one incoming to the operator's position and the other outgoing from the banks of the selector stage, both branches 105 adapted to be made busy at the main exchange when a junction is taken into use at the satellite exchange.

6. A telephone exchange system comprising a main exchange with register and a satellite exchange wherein the satellite exchange is of the tandem type having a plurality of satellites connected thereto, means for discriminating after two digits of a call to release the junction and register if the 110 call be local and to permit operation of the final finder switch of the satellite by the last two digits. 115

7. A telephone exchange system comprising a main exchange and a satellite exchange 120 of the tandem type to which lines are connected and having satellites connected thereto, a junction line extending to the main exchange and means for discriminating after reception of each digit if the call be outgoing. 125

In witness whereof, I hereunto subscribe my name.

WILLIAM HATTON.
